UNITED STATES PATENT OFFICE.

FLOYD TANNER, OF DRIFTWOOD, OKLAHOMA.

PUMP.

Application filed April 30, 1927. Serial No. 187,814.

This invention relates to pump attachments for securing air pressure pumps to barrels, tanks, drums, casks and the like.

Liquids, particularly fuel oil is usually 5 merchandised in barrels, drums or the like from the wholesaler to the dealer. The dealer dispenses the liquid in smaller quantities to the customer. The casks or drums are usually air tight so if air pressure is 10 placed on the liquid and a pipe is run into the barrel or drum, the air pressure will force the liquid through the pipe where its flow can be controlled by a valve, cock or faucet.

I have provided an attachment which may 15 be applied to and easily removed from commercial barrels or drums so that the liquid may be forced out by air pressure. Therefore, when a barrel or drum of oil or other liquid is received by the dealer, my invention 20 can be applied for the purpose of dispensing the liquid and when the barrel is empty, the attachment may be removed and applied to another full barrel or cask.

The novelty of the invention will be understood 25 by reference to the following description in connection with the accompanying drawings in which:

Fig. 1 is a perspective view of the attachment applied.

Fig. 2 is a sectional view through the 30 plug, the pipe for passing out the liquid and the air discharge pipe for supplying air from the pump so that the pump can force the air into the barrel or cask.

Referring, now, to the drawings by numerals of reference, 1 designates the barrel or cask having a relatively large hole or opening 2 which may be closed by the plug 3. 4 is a similar opening which may be closed 40 by a suitable plug not shown. This is all old construction and in itself constitutes no part of my invention.

My invention is illustrated as comprising 45 a pump cylinder 5 which with the piston 6 constitutes an air compressor for forcing air into the cask or barrel. The piston 6 may be provided with a valve 7 which opens on the up-stroke and which closes on the down-stroke of the piston. The upper end 50 of the cylinder 5 may be open to admit air into the cylinder. Secured to the bottom of the cylinder 5 is a nipple 8 to which is fastened a flexible conduit 9, in turn fastened to the nipple 10 of the air discharge pipe 11 which passes into the barrel or cask 55 below the plug 13. The plug 13 closes the

opening 4 when the pump is attached and it may be fastened to the pipe 12 which extends down to the bottom of the barrel or cask so that oil may be forced up through it into the flexible hose 14 having a valved faucet 15 on its end. The lower end of the pipe 12 is provided with a telescopic extension 16. This is provided because some barrels or casks have greater depths than others. The flexible conduit 9 is provided with an outwardly opening check valve 17 which is lifted off its seat for each down-stroke of the piston 6 and which seats upon each up-stroke of the piston 6. The piston 70 6 is operated through the medium of a piston rod 18 and a handle 19.

The air compressor, consisting of the cylinder and piston, is removably secured to the barrel or cask or drum by two yielding 75 clamps 20 and 21 having drum-engaging hooked ends 22 and 23. These clamps are yieldingly held together by a contracting coil spring 24. One of the clamps (20) is fast to the cylinder 5, therefore, when the 80 hooked ends of the clamps 20 and 21 are slipped over the ends of the barrel or other receptacle, the compressor will be securely fastened to it. When the plug 13 is screwed in the hole 4 with the plug 3 in place and 85 valve of the faucet 15 closed, the operator can force air on to the liquid by manipulating the piston. Since sufficient pressure has been generated upon the liquid, the valve 25 of the faucet 15 can be unseated so that the 90 liquid will be forced out of the faucet in a well understood manner. When the receptacle is empty, the plug 13 can be unscrewed so that the pipe 12 can be taken out and the two clamps 20 and 21 can be detached from 95 the receptacle ready to be applied to the next receptacle containing liquid. When it is desired to screw and unscrew the plug 13, the flexible conduit 9 can be detached from the nipple 10 and since the plug is in place, 100 the end of the flexible conduit 9 can be slipped back over the nipple 10.

From the foregoing it will be apparent 105 that I have provided an attachment easily attached to and removed from different kinds of barrels or drums so that the liquid may be dispensed under pressure. Since the device is capable of being applied to different kinds of containers, I shall refer in the claims to the container as a receptacle to 110 include any kind of container whether a barrel, drum or any equivalent structure.

What I claim and desire to secure by Letters-Patent is:—

1. A device of the class described comprising a pump, means for removably securing the pump to a drum-like receptacle, a discharge pipe, a bushing for securing the pipe to the receptacle so that one end of the pipe extends outside the receptacle, a curved pipe carried by the discharge pipe having its 10 inlet above the bushing and its outlet discharging through the wall of the discharge pipe below the bushing so that the curved pipe will discharge within the receptacle, and a conduit leading from the pump to the 15 curved pipe.
2. A device of the class described comprising a receptacle, a pump, two yieldingly alining clamps for securing the pump to the receptacle, a valved liquid receiving and discharge pipe, a bushing for connecting said pipe to the receptacle, a pipe carried by the discharge pipe having its inlet communicat-

ing with the pump above the bushing and its outlet discharging below the bushing into the receptacle so as to discharge into the 25 receptacle outside the liquid receiving and discharge pipe to thereby put pressure on the liquid within the receptacle.

3. A device of the class described comprising a pipe, a bushing carried by the pipe 30 intermediate its ends, one end of the pipe being submergible in the liquid and the other end having a discharge orifice, a pump, removable receptacle engaging clamp connected to the pump for securing the pump 35 to the outside of a receptacle, a curved pipe carried by the first named pipe having its inlet outside the first named pipe above the bushing and its outlet discharging outside the first named pipe below the bushing and 40 a conduit connecting the inlet of the curved pipe with the outlet of the pump.

In testimony whereof I affix my signature.
FLOYD TANNER.
